UNITED STATES PATENT OFFICE.

HENRY WOFFORD, OF CASPER, WYOMING.

COMBINED FAUCET AND CONTAINER.

Application filed March 28, 1921, Serial No. 456,387. Renewed October 14, 1922. Serial No. 594,658.

To all whom it may concern:

Be it known that I, HENRY WOFFORD, a citizen of the United States, residing at Casper, in the county of Natrona and State of Wyoming, have invented certain new and useful Improvements in Combined Faucets and Containers, of which the following is a specification.

The object of this invention is to provide a container with means for permitting a faucet to be conveniently and firmly attached.

Another object of this invention is to provide a container as above outlined with means for permitting the application of a faucet carrying a cutter, the latter being adapted to penetrate the wall of the container for causing a passage communicating with the passage through the faucet.

In addition to the above the invention consists in the provision of a cutter projecting from the threaded extension of a faucet and being spaced inwardly from such threads whereby an opening is formed in the container of less diameter than the diameter of the threads thus enabling an engagement by the latter with the walls of the container.

Reference will be had to the accompanying drawings forming a part of this specification and wherein like numerals of reference designate corresponding parts throughout the several views, in which:—

Fig. 1 is a sectional view through a section of a container and a sput, a faucet being shown in elevation partially engaging same.

Fig. 2 is a similar view showing the faucet further advanced.

Fig. 3 is a top plan view of the faucet and

Fig. 4 is an end view of the faucet.

Referring to the drawings reference numeral 1 indicates a section of a sheet metal container such as is at the present time used for the conveyance of liquid material. Located near the bottom of the container and projecting outwardly from one of the walls is the sput 2 which is permanently and rigidly fixed to the container by any suitable means such as by soldering.

The sput 2, may be formed of any suitable material capable of receiving threads and retaining such threads under pressure as it will be obvious that the forward movement of the faucet and the consequent per-

foration of the container by the cutter carried thereby will depend entirely upon the resisting qualities of such threads. In cases where the wall of the container is made of hard durable metal a sput of greater thickness may be utilized and thereby an increase in the number of threads may be obtained. By such increase in the number of threads a more forceful and resisting forward movement of the cutter is secured.

The inner face 3 of the sput 2, which engages the outer wall of the container is necessarily of suitable contour to engage containers or receptacles of various shapes. A threaded passage 4 is formed through the center of the sput and the outer face of such sput is gradually cut away to form the truncated cone-shaped structure.

A faucet 5 formed with the wrench grip 6 or flange 6 and the usual threaded extension 7 is provided with a cutter 8 as shown more clearly in Figure 4. This cutter 8 is spaced inwardly from the outer diameter of the threads on the extension 7 and the cutting edge 9 gradually extends longitudinally of the threaded extension beginning at the termination of the threads on such extension. By this arrangement, the cutting edge merges into the outer end of the thread of the extension 7 and in use, a circular opening is sheared through the wall of the can of less diameter than the threads on the extension 7 and accordingly the threads engage the wall of the opening at 10 and bind the same against the inner wall 3 of the sput.

Referring to the cutter 8 attention is directed to the fact that the outer peripheral face of same is equi-distant from the longitudinal axis of the faucet and that this face, which is indicated by the reference character 11, terminates in the cutting edge 9. The thickness of this cutter increases from the cutting edge 9 until the cutter merges with the wall of the faucet extension, at which point, the thickness corresponds to the distance from the base of the outer threads on the extension 7 to the wall forming the passage through the faucet.

By reference to the foregoing construction the following application and utilization will be obvious. A container is prior to shipment or subsequently provided with a sput of the type described and indicated by the numeral 2. This sput is necessarily located near the bottom of the receptacle to

permit the removal of all of the contents without unnecessary manipulation. When it is desired to open the receptacle, the threaded extension 7 of the faucet is attached to the thread of the sput, and the faucet is rotated to move the cutter 8 through the passageway of the sput until the cutting edge engages the wall of the container. Then further rotation of the faucet will cause the cutting edge to make a circular incision in the wall of the receptacle and finally cut a disk 14 from said wall which will fall into the receptacle. It will be seen in this connection, that the thickness of the sput is sufficient to permit the firm engagement of a number of coils of the threads of the sput and the extension 7 before the cutter comes in contact with the wall of the container. This feature is more readily discernible by examination of Figure 1 in which the faucet extension is shown engaging two of the threads of the sput and the cutter still spaced from the wall of the container.

With the parts in position as shown in Figure 1 a continued rotation of the faucet will cause the cutter to slowly penetrate the receptacle and due to the fact that the length of the cutter exceeds the distance covered by the number of threads engaged in a complete revolution of the faucet, such cutter will make more than a complete turn through the wall of the can, thereby insuring the formation of a circular passage through the wall corresponding to the opening in the faucet, by the removal of the disc 14 shown in Figure 2.

It is well known that heretofore numerous efforts have been made to accomplish the results secured by the construction and arrangement above outlined but in no instance has success been attained.

By the construction above outlined the engagement of the threads of the faucet with the threads within the passage formed in the sput cause a forward movement of the cutter which is in connection with the cutter construction the means whereby a predetermined and regular opening is formed in direct communication with the passage of the faucet. As the thread of the extension 7 merges into the rear end of the cutting edge of the cutter 8, it will be seen that the thread of said extension is auto-

matically guided into the hole formed by the cutter, and the edge of said hole then functions as a thread, to grip the thread of the extension 7. The engagement of the wall of the container by the threads on the faucet extension also insures a complete and permanent binding between the sput and the container as long as the faucet is in position and any lateral movement of the faucet will not cause the accidental removal of the sput. This is a very important feature of the invention, and is only possible through the particular arrangement of the cutter.

What I claim as new and useful and desire to secure by Letters Patent, is:

1. The combination with a container having a threaded sput permanently fixed thereto, of a faucet having a threaded extension designed to engage the threads of said sput for moving the faucet toward and securing the faucet to said container said sput being permanently held in place independently of said faucet, and a cutter mounted on the forward end of said extension and adapted to cut a hole in said container as said extension is moved toward the container, said cutter being provided with a helically arranged cutting edge, extending in the same direction as the thread of the threaded extension and forming a continuation of said thread. 85

2. The combination with a container having a sput permanently fixed thereto and provided with internal threads, of a removable faucet having a threaded extension designed to engage the threads of the sput for moving said extension toward the container when the faucet is turned relatively to said container, and a cutter integral with the end of said extension and forming a continuation of the threads of said extension, said cutter being adapted when the extension is moved into said sput to form a circular aperture in a wall of said container to permit the thread of said extension to engage said wall, and said sput being held in engagement with said container independently of said faucet. 95

In testimony whereof I hereunto affix my signature in the presence of two witnesses.
